(57) **CLAIM**

The ornamental design for a vehicle wheel, as shown and described.

DESCRIPTION

FIG. 1 is a front view of a vehicle wheel showing my new design.

FIG. 2 is a perspective view thereof;

FIG. 3 is a front view of a second embodiment of a vehicle wheel showing my new design; and,

FIG. 4 is a perspective view of the second embodiment of a vehicle wheel showing my new design.

The broken line showing of environment in FIG. 1-4 is for illustrative purposes only and forms no part of the claimed design.
